UNITED STATES PATENT OFFICE.

JEROME D. JEFFERSON, OF FEDERALSBURG, MARYLAND, ASSIGNOR TO DEL-MAR-VA SALES COMPANY, OF LAUREL, DELAWARE.

IMPALING TRAP.

Application filed March 9, 1927. Serial No. 173,829.

This invention relates to an impaling trap, and particularly to a construction including a sliding impaling member associated with a retaining trigger adapted to be released by 5 an animal coming in contact with a portion thereof. In traps of this character it is desirable to protect the user from accidental injury due to contact with the impaling pins, either in handling, baiting, or setting the 10 trap. I therefore provide the frame of the impaling pin with a projecting spring which is also connected to the retaining trigger so as to automatically set the trigger as the pin is retracted to engage the trigger finger 15 with a retaining plate upon the frame of the pin. The supporting frame or block is also formed with an opening for access to the bait holder of the trigger so that it may be manipulated without danger of injury from the 20 pins when in retracted position, and this block is further formed with an abutment which cooperates with such impaling pins when projected.

The construction as developed is adapted 25 to be economically manufactured and provides a support for the sliding pins and their pivoted trigger in cooperation with the abutment to be engaged by said pins.

The invention has for an object to provide 30 a novel and improved construction of impaling trap including a base having a sliding impaling pin thereon which is retained in retracted position by a trigger member, such trigger and pin being connected by a spring 35 to insure joint operation thereof and effect the automatic setting of the trigger as the pin is retracted.

A further object of the invention is to provide 40 a construction of support provided with an abutment and a spaced surface upon which the sliding frame of an impaling pin is mounted, together with a pivoted trigger cooperating with a retaining plate carried by the frame of the impaling pin.

Another object of the invention is to provide 45 a construction in which the trigger member with its bait carrying portion and retaining finger may be formed of a single piece of material while the impaling pins 50 are formed of a U-shaped frame connected adjacent the pins by a retaining plate having a lip thereon adapted to engage and ride over the trigger in the retracting movement of the pins.

Other and further objects and advantages 55 of the invention will be hereinafter set forth and the novel features thereof defined by the appended claims.

In the accompanying drawing: 60
 Figure 1 is a plan of the trap;
 Figure 2 is a side elevation thereof;
 Figure 3 is a section on the line 3—3 of 65 Figure 1;
 Figure 4 is a central longitudinal section;
 Figure 5 is a detail perspective of the frame of the impaling pins;
 Figure 6 is a similar view of the trigger and tension spring; and
 Figure 7 is a section on the line 7—7 of 70 Figure 4.

Like reference numerals designate corresponding parts throughout the several figures of the drawing.

The invention is adapted for various 75 applications and may be supported upon a base or block of suitable design. In the present instance a preferred form is shown in which the block 10 is provided at one end with an abutment 11 adapted to cooperate with one or more impaling pins 80 12 which are slidably mounted upon the horizontal upper face 13 of the body of the block. If desired the abutment may be provided with impaling pins 14 rigidly mounted therein which cooperate with the pins 12 as the animal is forced toward the 85 abutment by the movement of the sliding pins.

The impaling pins may be varied in number and in the form shown the frame 90 thereof is substantially U-shaped, the bend 16 forming a suitable handle for its retraction, while the frame is held in its sliding relation with the surface 13 by means of keepers 17 embracing the same. The frame 95 15 is provided adjacent the pins 12 with a retaining plate 18 secured thereto and having an overturned edge 19 adapted to cooperate with the finger 20 of the pivoted trigger 21. This trigger may be mounted 100 in a kerf or way 22 formed in the body 10 of the base and comprises a single piece of wire having at its free end a bait retaining plate 23 and bent upon itself at 24 to receive an actuating spring 25 which extends therefrom to a link or eye 26 at the bend 16 of the pin frame.

The rebent portion of the trigger is

formed with a pivoting seat 27 and the upwardly projecting retaining finger 20 adapted to engage the edge 19 of the plate 18 carried by the fingers. This trigger is 5 pivotally mounted in a novel manner by means of a pin 29 which is loosely inserted in an aperture 30 of the block and retained in position therein by a driven device 31 intersecting the aperture 30. If it be desired to remove the trigger the device 31 is withdrawn and the pin will gravitate outward through the passage 30 when the base is suitably inclined. By connecting the pins and trigger through the spring member 15 25 a joint operation is effected which causes the automatic setting of the trigger and in this retracting movement of the pin the plate 18 rides over the retaining plate of the pin until it is thrown into engagement 20 with the outer edge thereof by the increasing tension of the spring. In order to suitably depress the finger of the trigger during this movement an upwardly deflected lip 32 is provided upon the plate 18 which 25 causes the plate to ride over the finger until the latter reaches an engaging position. The block is also provided with an opening 33 by which convenient access may be secured to the trigger in order to arrange the bait 30 thereon or determine a sensitive setting thereof without danger of the operator coming into the field of action of the impaling pins and being injured thereby in case of accidental release of the pins.

35 The operation of the invention will be apparent from the foregoing description from which it will be seen that the trigger may be very sensitively set so that the slightest contact therewith either in removing the bait or otherwise will trip the trigger finger from the retaining plate and permit the full tension of the spring to project the pins which impale the animal and force it into contact with the cooperating pins upon the abutment member.

45 The construction shown presents a simple, efficient, and economically manufactured form of trap in which the base provides a suitable abutment with a supporting surface for the sliding pins and pivotal mounting for the trigger while the pin member is adapted to be formed from a single piece of material having its free ends connected by the retaining plate and the trigger member similarly formed from a rebent strand providing the bait support, the trigger pivot, the spring connection and the retaining finger. Such construction by directly connecting the trigger with the impelling 55 spring for the pins provides an automatically operating construction which avoids the danger of setting such a trap.

60 The details of construction have been shown and described but the invention is 65 not confined thereto as changes and alter-

ations may be made without departing from the spirit of the invention as defined by the following claims.

Having thus described my invention, what I claim as new and desire to secure by Letters Patent is:—

1. An impaling trap comprising a base, a sliding impaling pin mounted thereon, a trigger member for retaining the pin in retracted position, and a spring having a permanent connection with the trigger and pin to effect the automatic engagement of the trigger with the pin when the pin is retracted. 75

2. An impaling trap comprising a base, a sliding impaling pin mounted thereon, a trigger member for retaining the pin in retracted position, a spring connecting the trigger and pin to effect joint operation thereof, and an abutment carried by the base opposite the free end of the impaling pin and provided with a fixed impaling pin. 80

3. An impaling trap comprising a base having an abutment, a sliding impaling pin mounted upon said base and provided with a retaining plate, a pivoted trigger having a bait carrying arm and a finger disposed to engage said plate, and a tension spring extending from said trigger to said impaling pin. 85

4. An impaling trap comprising a base having an abutment, a sliding impaling pin mounted upon said base and provided with a retaining plate, a pivoted trigger having a bait carrying arm and a finger disposed to engage said plate, a tension spring extending from said trigger to said impaling pin, and means upon said retaining plate to cause the same to depress the finger of the trigger in the retracting movement of the pin. 95

5. An impaling trap comprising a base having a supporting surface, parallel impaling pins connected together and slidably mounted upon said surface, a retaining plate extending between said pins adjacent the free end thereof, a pivoted trigger including a bait arm and a retaining finger to engage said plate, and a spring extending from the rear of the pivot of said trigger into engagement with the connected pins. 105

6. An impaling trap comprising a base having a supporting surface, parallel impaling pins connected together and slidably mounted upon said surface, a retaining plate extending between said pins adjacent the free end thereof, a pivoted trigger including a bait arm and a retaining finger to engage said plate, a spring extending from the rear of the pivot of said trigger into engagement with the connected pins, and a lip upon said plate adapted to engage and depress said finger in the retracting movement of the pins. 110

7. An impaling trap comprising a base, sliding impaling pins mounted thereon and 115

comprising a U-shaped frame connected at its free ends by a retaining plate, keepers for retaining said plate in sliding relation to the base, a trigger member cooperating with said plate, and tension means for said pins.

8. An impaling trap comprising a base, sliding impaling pins mounted thereon provided with a retaining plate, an integral trigger member including a bait carrying arm at one end and a rebent opposite end forming a retaining finger and pivoting socket, and a tension spring extending from the rebent end of said trigger to the impaling pin.

9. An impaling trap comprising a base, sliding impaling pins thereon provided with a retaining plate, an integral trigger member including a bait carrying arm at one end and a rebent opposite end forming a re-

taining finger and pivoting socket, a tension spring extending from the rebent end of said trigger to the impaling pin, a pivot for said trigger removably disposed in a recess in the base, and means for retaining said pivot against removal from said recess.

10. An impaling trap comprising a base having at one side a horizontal supporting surface, spaced by an intermediate recess from an abutment at the opposite end of the base, said spaced portion being provided with an aperture to permit access thereto, a sliding impaling pin mounted upon the supporting portion to engage the abutment, and a trigger engaging said pin and disposed intermediate the pin and aperture and in alignment with said aperture.

In testimony whereof I affix my signature.

JEROME D. JEFFERSON.
